GEORGE BURCH, OF NEWARK, NEW JERSEY.

Letters Patent No. 91,081, dated June 8, 1869.

IMPROVEMENT IN THE MANUFACTURE OF BRACELETS.

The Schedule referred to in these Letters Patent and making part of the same.

To all whom it may concern:

Be it known that I, GEORGE BURCH, of the city of Newark, in the county of Essex, and State of New Jersey, have made certain Improvements in Bracelets; and declare the following, taken in connection with the accompanying drawings, to be a full, clear, and exact description of the same.

The nature of my improvement consists in the construction of bracelets, rings, and similar forms from a single strip of metal with edges rounded inwardly, and in the adaptation of dies to the hitherto unattained object of forming, from a single piece of metal, in one process, perfect round edges to oval or elliptical bracelets, or to round finger-rings.

Every jeweller is aware of the unprofitableness of attempts to bend a straight piece of metal with round turned edges into round, oval, or elliptical forms, it being next to impossible to preserve or attain a smooth bending on the edges when turned or bent; therefore, when round-edged bracelets are desired, they are made in parts and soldered together.

To attain the object of rounding from a single piece of metal, the edges of bracelets or of similar forms, a case of iron, steel, or other metal, is constructed in the form desired for the outside of the bracelet, thick enough not to spring, and is hinged to open, being closed by the bolts *a*, shown in Figure 3, which represents the case or form.

A strip of metal of suitable width and length is

formed into a ring, and the ends soldered together and placed in the case or form, and the case is bolted securely.

Dies are fitted with nicety to the inside of the case or form, one above, and the other below, the strip of metal being between the two. Around the edge of the face of the die a recess, nearly semicircular in its depth, and of the width necessary to form the bead or round of the desired size, is made, and is shown at Figure 2, and the same in section at Figure 4.

Pressure is applied to the dies, which has to be nicely equalized, the force turning the edges of the strip as nearly round as possible by means of the recess in the edges of the dies, as shown in the section 6 of the bracelet, Figure 1.

I do not claim the means simply by which the desired object is attained.

What I claim, and desire to secure, is—

1. The construction of bracelets, rings, or similar forms from a single strip of metal, with edges rounded inwardly, substantially in the manner set forth.
2. The combination of the dies, constructed as described, with a case, A, or its equivalent, for the purposes set forth.

GEO. BURCH.
